UNITED STATES PATENT OFFICE.

ERICH F. W. MEYER, OF MEMPHIS, TENNESSEE.

GARMENT-FASTENER.

SPECIFICATION forming part of Letters Patent No. 687,326, dated November 26, 1901.

Application filed April 11, 1901. Serial No. 55,371. (No model.)

To all whom it may concern:

Be it known that I, ERICH F. W. MEYER, a citizen of the United States, residing at Memphis, Shelby county, State of Tennessee, have invented certain new and useful Improvements in Garment-Fasteners, of which the following is a specification.

My invention relates to certain new and useful improvements in garment-fasteners and devices for securing buttons to clothes.

My invention has for its objects to provide an improved form of clasping device whereby two garments may be secured together or a button be attached to a garment and to provide novel means for this purpose whereby the button may be attached at any part of the garment without forming a knot or similar protuberance at the point of attachment.

With the above objects in view my invention consists in the novel construction and combination of parts, as hereinafter more fully set forth in the drawings, specification, and claims.

In the drawings, Figure 1 is a section on the line I I of Fig. 5, showing the garment-fastener catching together a portion of two garments. Fig. 2 is a mechanical perspective of the garment-fastener. Fig. 3 is a side elevation showing the device as a button-fastener. Fig. 4 is a section on the line IV IV of Fig. 5. Fig. 5 is a plan view of the garment-fastener. Fig. 6 is a section on the line VI VI of Fig. 5.

Referring now to the drawings, in which like numerals indicate the same or like parts in all the views, the fastener consists of a bottom or locking plate 1 and a top or hook-carrying plate 2, pivoted together by pins 3 on the hook-plate adapted to turn in bearings 4 on the said locking-plate. Hooks 5, concentric with the pins 3, are carried by the plate 2, which hooks engage and pass through the cloth of the garments to be fastened together and bring them up into the opening 6 through the locking-plate 1. This opening 6 is of slightly greater length than twice the distance from the pins 3 to the outside of the hooks 5—that is, the length of the opening is slightly greater than the diameter of the hooks. This opening, too, is located equally

on each side of or concentric with the said pins or pivots 3 and is slightly wider than the outside of the hooks, so that they may move freely through it.

7 represents the locking-lugs on the locking-plate 1, which lugs are bent outward at the point 8, Figs. 2 and 4, to permit the entrance of the hook-plate 2 and then inward at 9 to engage the beveled edges 10 of same.

11 and 12 are ears extending out from the plates 1 and 2, respectively, and preferably brought into the same plane, each ear occupying about one-half of the width of the plate, the ear 11 from the bottom plate 1 being preferably at the right and the ear 12 at the left-hand side of the plate, looking from the said ears toward the hooks. While it is by no means necessary that these ears be brought into the same plane nor that they be on the sides shown, such an arrangement is much to be preferred, as it makes the disengagement of the fastener when desired much easier.

13 is a shield which extends upward from the bottom plate 1 and is curved over to cover the points of the hooks 5.

14 is the cloth of the garments to be caught together.

In Fig. 3 I show my fastener as a button-fastener, 1 and 2 being, as in the other views, the locking and hook plates, respectively, 80 and 15 the button. The dash-and-dot line 16 is an extension from the shield 13 to show the manner in which the button clears same when it is being put on or taken off.

In Fig. 6 I show a sectional view of the fastener as it appears when being fastened to or removed from the cloth. In this view the hooks 5 have just been inserted through the cloth 14 and are slightly raising the cloth into the opening 6. As the ear 12 of the button is pushed backward the hooks 5 enter the cloth again and pass upward through it into the opening 6. In doing this they raise the cloth into the said opening, as shown in Fig. 1, so that the bottoms of the cloth and of the hooks come flush. The hooks 5 are semicircular in form, with a pivot 3 at the center of the circle. When, therefore, they are inserted in the cloth and the fastener is being closed, they move through the cloth without knotting it 100

up or drawing it in any manner other than to raise it slightly into the opening 6, and since, as before stated, the bottoms of the hooks and of the cloth are flush there is no 5 protuberance to discommode the wearer.

To attach the fastener, it is only necessary to take same in the position shown in Fig. 6, insert the hooks 5 through the cloth, and close the ears 11 and 12 together. The beveled 10 edges 10 of the plate 2 engage with the lugs 7 and hold the fastener on. To remove the fastener, the ears 11 and 12 are grasped, the ear 11 being pushed down and the ear 12 up to disengage the bevel edges 10, and the plate 15 2 is thrown forward and the hooks 5 withdrawn from the cloth.

Different arrangements of the locking-lugs and of the unlocking-ears may be employed without departing from the spirit of my invention. More or less hooks than the three shown may be used, if desired; but I find that the number shown is most satisfactory. Parallel cuts may be made for these hooks to pass through or openings near the point and 25 back only; but, as in the number of hooks, I find the open space shown as most satisfactory.

Having now fully described my invention, what I claim, and desire to secure by Letters 30 Patent of the United States, is—

1. In a garment-fastener, the combination with a base-plate, bearings extended upward at the side of said base-plate and an opening through said base-plate equally disposed on 35 each side of said bearings, of a plate pivoted in said bearings, hooks fastened to said plate concentric with said pivots and extending through the said opening, means of locking the plates together, and unlocking-ears extending from said plates, substantially as shown and described.

2. In a garment-fastener, the combination with a base-plate, bearings extended upward at the side of said base-plate, and an opening 45 through said base-plate equally disposed on each side of said bearings, of a plate pivoted in said bearings, hooks fastened to said plate concentric with said pivots and extending through the said opening, means of locking 50 the plates together, and an ear of about one-half the width of the plate extending from

each plate and being bent into the same plane, substantially as shown and described.

3. In a garment-fastener, the combination with a base-plate, bearings extended upward 55 at the side of said base-plate, an opening through said base-plate equally disposed on each side of said bearings, and lugs extending upward from said base-plate, of a plate pivoted in said bearings, hooks fastened to 60 and extending beneath said plate and through said opening, said hooks being concentric with said pivots, and beveled edges to engage said lugs on said base-plate, substantially as shown and described. 65

4. In a garment-fastener, the combination with a base-plate, bearings extended upward at the sides of said base-plate, an opening through said base-plate equally disposed on each side of said bearings, and lugs extended 70 upward from the sides of said base-plate, of a plate pivoted in said bearings, hooks fastened to said base-plate and extending beneath same and through the said opening, 75 said hooks being concentric with said pivots, beveled edges to engage with said lugs, and a lug extending from each of said plates to disengage said plates, substantially as shown and described.

5. In a garment-fastener, the combination with a base-plate, bearings extended upward at the sides of said base-plate, an opening through said base-plate equally disposed on each side of said bearings, and lugs extended upward from the sides of said base-plate, of 80 a plate pivoted in said bearings, hooks fastened to said base-plate and extending beneath same and through the said opening, 85 said hooks being concentric with said pivots, beveled edges to engage with said lugs, and 90 an ear extending from each of said plates, said ears being of one-half the width of the plates and having their ends brought into the same plane substantially as shown and described. 95

In testimony whereof I have signed my name to this specification in the presence of two subscribing witnesses.

ERICH F. W. MEYER.
